UNITED STATES PATENT OFFICE.

NATHAN P. STEVENS, OF BOSTON, MASSACHUSETTS.

IMPROVEMENT IN PISTONS FOR STEAM-ENGINES.

Specification forming part of Letters Patent No. 44,674, dated October 11, 1864.

To all whom it may concern:

Be it known that I, NATHAN P. STEVENS, of Boston, in the county of Suffolk and State of Massachusetts, have invented a new and useful Improvement in the Pistons of Engine-Cylinders; and I do hereby declare the same to be fully described in the following specification, and represented in the accompanying drawings, of which—

Figure 1 is a side view, and Figs. 2 and 3 transverse sections, of a piston-head provided with my invention, Fig. 2 being taken in a plane in line with the axis of the head, while Fig. 3 is taken in a plane cutting the said plane at right angles and going through the ring and its groove, to be hereinafter described.

My improvement has reference to an engine-piston provided with one or more metallic packing-rings. As the head of such a piston is usually made, it is not only provided with one or more steam-passages leading through its opposite ends and into a steam chamber or space within it, (the head,) but it also has one or more passages leading through its circumference and into the ring-space thereof, the same being in order that the steam of the cylinder may enter the chamber through the passage or passages in its end or ends, and pass from such chamber into the ring, groove, or space, and act against the packing-ring in order to expand it.

In carrying out my invention in whole I have a close chamber within the piston-head—that is, such chamber has no opening leading through either of the ends of the piston by which steam from the cylinder can pass through such end and into the chamber, but it has one or more openings leading out of it and into the ring space or groove. Furthermore, the ring has a width a very little less than that of its groove, in order that steam may pass between one side of the ring and one side of the groove, and thence around within the ring space or groove and into the close steam-chamber within the head. This close steam-chamber is intended to retain steam, which is to act as a spring to expand the ring or keep it expanded during the period which intervenes between the exhaust of the steam on one end of the piston-head and the reception of steam on the other end thereof. In all steam-engines there is

such an interval, which is caused by the exhaust-port being opened before the receiving-port is opened. After the exhaust-port has been opened the piston-head still has to travel a short distance ere the steam is next brought against it, and were the ring not kept expanded by the steam in the close chamber the steam, when entering the cylinder, would expand the ring suddenly and be liable to break or otherwise injure it. While the piston is in the act of being driven by the steam part of such steam will be entering the close chamber, the ring being expanded by the steam. The ring will first be expanded by the steam passing into the groove of the said ring, after which, and while the piston may be moving in its stroke, the steam will pass into the close chamber, it entering the chamber through the opening leading into it from the ring-groove. This steam will not be lost from the close chamber immediately when the exhaust takes place, for it requires an interval of time for it to get out of the chamber, corresponding to that which was required for it to get into such chamber. Now, this interval is longer than the period which intervenes between the exhaust of the steam on one end of the piston and its introduction to the other end. Consequently the expansive power of steam within the close chamber of the head will operate to keep the ring expanded, and thus prevent its too sudden expansion by the entering steam.

In the drawings, A denotes the piston-head, within the circumference of which there is a groove, *a*, for holding an annulus or ring, *b*, both groove and ring being either square or rectangular in cross-section.

In the bottom of the groove *a* there is an annular projection, *c*, which goes around the entire head. A small opening or passage, *d*, leads from the ring-groove directly into a close chamber, *e*, made within the piston-head. The ring is cut open at its lower part, each end of the ring being formed with a semicircular notch to abut against and embrace a curved pin, *f*, which is inserted in the piston-head and serves to prevent the ring from revolving around within the ring-groove of the head. The hole or passage *d* may have a diameter somewhat greater than the width of the projection *c*, in order that the steam

may be able to enter the passage. The object of the annular projection is to prevent the mouth of the passage *d* from becoming closed by the ring, which would be likely to occur were there no such projection. Thus, the projection insures the entrance of the steam into the passage *d*. With a piston-head so made, only one packing-ring becomes necessary, and this will be kept properly expanded during the entire stroke of the piston. The packing-ring, by being of a less width than the groove, will vibrate therein or first be forced to one side of the groove during one stroke of the piston, and next be forced against the other side of the groove during the next stroke of the piston. This will en-

able the steam to get under the ring so as to expand it; therefore

I claim—

1. The improved piston or piston-head, as made with the vibratory ring and its groove, and the steam-tight chamber opening into the said groove, the whole being in manner and so as to operate as described.

2. The combination of the annular projection *c*, or its equivalent, with the vibratory ring and its groove, and the steam-tight chamber and its opening.

N. P. STEVENS.
